CLAIM

The ornamental design for a yoni steamer stool, as shown and described.

DESCRIPTION

FIG. 1 is a perspective view of a yoni steamer stool showing our new design;

FIG. 2 is a front elevation view thereof;

FIG. 3 is a rear elevation view thereof;

FIG. 4 is a side elevation view thereof, the opposite side being a mirror image of the shown;

FIG. 5 is a top plan view thereof; and,

FIG. 6 is a bottom plan view thereof.

In the drawings, the broken lines depict environmental subject matter and form no part of the claimed design.
